SAFETY CATCH FOR VERTICALLY SLIDING DOORS

Charles C. Moler, Hartford City, Ind., assignor to
Overhead Door Corporation, Hartford City, Ind.

Application August 18, 1950, Serial No. 180,269

5 Claims. (Cl. 20—19)

1

This invention relates to improvements in safety catch for vertically sliding doors.

The principal objects of this invention are:

First, to provide an improved form of safety catch for vertically sliding doors having guide rollers travelling in a track, which catch coacts with the track with successively engageable teeth so that the catch has a dual or emergency locking engagement should the first tooth fail or slip.

Second, to provide an improved form of safety catch and guide track combination for a sliding door having a first frictional or wedging locking engagement and a second piercing engagement with a corner of the track should the first engagement slip due to spreading or bending of the track.

Other objects and advantages relating to details of my invention will be apparent from a consideration of the following description and claims. The drawings, of which there are two sheets, illustrate a preferred form of my safety catch as installed on a vertically slidable door.

Fig. 1 is a fragmentary inside elevational view of one side of a vertically slidable door with my safety catch installed thereon.

Fig. 2 is an enlarged fragmentary end elevational view of the door partially broken away in vertical cross section along the plane of the line 2—2 in Fig. 3 and illustrating details of the safety catch.

Fig. 3 is a fragmentary horizontal cross sectional view through the safety catch structure taken along the plane of the line 3—3 in Fig. 2.

Fig. 4 is a fragmentary end elevational view partially broken away in vertical cross section along the plane of the line 4—4 in Fig. 5 showing the safety catch in actuated door holding position.

Fig. 5 is a fragmentary horizontal cross sectional view through the catch in actuated position and taken along the plane of the line 5—5 in Fig. 4.

My safety catch consists of certain improvements in and additions to the safety catch of similar design disclosed and claimed in Patent No. 2,185,828 issued January 2, 1940, to Herbert Cady Blodgett for Safety Catch for Vertically Sliding Doors.

My catch is designed to be used in conjunction with the now familiar type of vertically sliding door in which a plurality of horizontally hinged door sections 1 are provided with pintle or shaft bearings 2 at vertically spaced intervals supporting the roller shafts 3. The shafts 3 carry rollers, not illustrated, which are received in and guidingly supported by the channel shaped guide rail 4. The guide rail has a vertically extending reach 5 secured to the walls or casing along the side of the door opening by mounting brackets 6. A horizontally extending shaft 7 is mounted above the door opening and provided with a pulley 8 for taking up the supporting cable 9. The shaft 7 may be power operated or as is illustrated in Fig. 1 may have a spiral spring 10 wound therearound

2

to counterbalance the weight of the door. The foregoing construction is now well known and so is not described in greater detail.

The lower door section 1 carries a mounting plate 11 at its lower end from which the angle shaped cable connecting flange 12 projects laterally of the door and inwardly of the door opening. A reinforcing plate or bracket 13 is welded to the plate 11 and flange 12 and projects beyond the flange 12 to form a retaining yoke for receiving the lower end of the cable 9. The cable is secured in the yoke by means of the bolt 14 and a suitable clamp 15 forming a loop in the cable.

Secured to the mounting plate 12 below the plate 13 is an angle shaped bracket 16, the inwardly projecting flange of which is apertured and coacts with the inwardly extending flange of the cable connecting flange 12 to support a short shaft 17. The laterally projecting end of the shaft 17 is rigidly connected to a generally circular roller-like catch 18 which is received between the flanges of the channel rail 4. Non-rotatably secured to the shaft 17 adjacent to the rail 4 is a generally L-shaped lever 19 having a laterally outwardly extending arm 20 on its upper end. The arm 20 carries an eye bolt 21 or other hooked fixture for embracing the supporting cable 9. A coil spring 22 wrapped around the shaft 17 has one end fixed to the bracket 16, and its other end fixed to a collar 23 secured to the shaft for biasing the shaft and lever 19 away from the door and cable 9. The engagement of the cable 9 in the eye bolt 21 obviously prevents rotation of the shaft and lever so long as the cable is taut. However, should the cable break or the balancing or lifting mechanism on the shaft 7 become inoperative, the cable 9 will be immediately loosened so that the spring 22 can rotate the shaft 17 and catch member 18.

Projecting radially outwardly from the periphery of the catch 18 and at an oblique angle to the axis of the shaft 17 is the tooth element 24 consisting of a hardened and pointed steel pin. The tooth 24 is mounted on the catch member 18 in such a position as to be in a downwardly directed location when the lever 19 is engaged with the cable 9 as is shown in Fig. 2.

Approximately opposite from the tooth 24, the catch 18 is provided with a cam-like projecting portion 25. Angularly advanced around the catch 18 from the tooth element 24 are a pair of teeth elements 26. The teeth 26 project radially from the catch 18 and normal to the axis of the shaft 17. The forward or outer flange of the guide rail 5 opposing the teeth 26 is provided with a series of slots or apertures 27 which are arranged to receive the teeth 26. Both the pair of teeth 26 and the single tooth 24 are held out of engagement with the track 5 by reason of the engagement of the cable 9 with the eye 21 on the lever 19.

Upon failure of the cable 9 or the sustain-

ing mechanism of the door, the cable is immediately slackened, thus permitting the spring 22 to rotate the catch 18 so that the projection 25 bears against the inner flange of the guide rail. Simultaneously the pair of teeth 26 are rotated against the forward flange of the guide rail, and pressure of the cam projection forces the teeth 26 into the first slot 27 encountered by the teeth in the downward movement of the door. Positive interlocking of the teeth 26 in the slot 27 causes the catch member 18 to rotate further tightly wedging the cam projection 25 against the inner flange of the rail. This wedging action should stop the descent of the door. However, should the flanges of the guide rail spread under the impact and force of the cam projection 25, the door may continue to descend. If this contingency occurs, the teeth 26, which remain in engagement with the slot 27, will cause further rotation of the catch member 18 until the single oblique tooth element 24 engages and partially penetrates the inner front corner of the guide rail. It will be noted that the tooth 24 is longer than the teeth 26 so that its engagement with the inside of the guide rail serves to force the catch member 18 and cam projection 25 further inwardly against the inner flange of the guide rail. Since most of the momentum of the descending door will have been checked by preliminary engagement of the teeth 26 and cam projection 25, the additional pressure of the cam projection against the inner flange of the rail will be sufficient to bring the descending door to a stop.

In order to release the catch from the rail, it is then necessary to raise the door manually and reestablish the tension in the cable 9 by suitable repairs so that the cable will hold the lever 19 and catch member in operative position.

I have thus described a highly practical inexpensive form of safety catch having the desired double catch safety feature so that others may understand the construction and operation thereof. I have not attempted to show other possible variations or modifications of my catch, but I do not intend to limit my invention to the particular form of catch illustrated and intend to limit my invention only as set forth in the following claims.

Having thus described my invention, what I claim as new and desire to secure by Letters Patent is:

1. A safety door catch for a vertically slidable door having a vertically extending guide rail of channel shaped cross section positioned along the edge of the door and a cable secured to the bottom of the door adjacent to said guide rail for lifting and sustaining the door, said catch comprising a shaft rotatably supported near the bottom of said door and projecting laterally into the channel of said guide rail, a catch member secured to said shaft within said channel, spring means biasing said shaft and catch member rotatively, a lever secured to said shaft and having an interlocking engagement with said cable remote from said shaft to resist said spring means so long as said cable is taut, a first tooth projecting from said catch member at a radial angle with respect to said shaft, and a secondary tooth projecting radially and obliquely with respect to said shaft and angularly displaced on said catch member behind said first tooth, said second tooth having a hardened point adapted to engage the corner of said rail when

said lever is released, one flange of said rail having a multiplicity of vertically spaced apertures formed therein to receive said first tooth and wedge said catch member in said rail to restrain said door from further lowering motion.

2. Safety catch mechanism for a vertically slidable door having a channel shaped guide rail along the side thereof and a lifting and sustaining cable secured to the bottom thereof, said mechanism comprising a rotatable catch member mounted on said door and projecting into the channel of said rail, said catch member having a projecting portion thereon rotatable into wedging engagement with a flange of said rail, spring means biasing said catch member into wedging position, a lever secured to said catch member and engageable with said cable to render said spring means inoperative when said cable is taut, a first rail engaging tooth on said catch member projecting radially from the opposite side thereof from said projection and a secondary tooth projecting radially from said catch member and at an oblique angle to the axis of said catch member to engage the interior corner of said rail and positioned angularly behind said first tooth, said other flange having a plurality of vertically spaced recesses formed therein for receiving and engaging said first tooth.

3. Safety catch mechanism for a vertically slidable door having a channel shaped guide rail along the side thereof and a lifting and sustaining cable secured to the bottom thereof, said mechanism comprising, a rotatable catch member mounted on said door and projecting into the channel of said rail, said catch member having a projecting portion thereon rotatable into wedging engagement with a flange of said rail, spring means biasing said catch member into wedging position, a lever secured to said catch member and engageable with said cable to render said spring means inoperative when said cable is taut, and a rail engaging tooth on said catch member projecting radially from the opposite side thereof from said projection and at an oblique angle to the axis of said catch member to engage the interior corner of said rail and positioned angularly behind said first tooth.

4. A safety catch for vertically slidable doors comprising, a rotatable catch member projecting from the side of said door, spring means biasing said catch member to locking position, a channel shaped rail disposed along the side of said door and within which said catch member is translatable, a wedging projection on said catch member engageable with one flange of said rail, and a tooth projecting from said catch member oppositely from said projection, the other flange of said rail having a plurality of vertically spaced holes formed therein for receiving said tooth.

5. A safety catch member for a vertically slid able door comprising a rotatable element carried by said door and spring biased to locking position, a wedging projection on said catch member and a pointed tooth projecting from said member radially opposite said projection and inclined obliquely to the axis of said catch member to engage the interior corner of a guide rail for said door.

CHARLES C. MOLER.
